ANIMAL FIGURE

David M. Kinniburgh, Chicago, Ill.

Application March 27, 1959, Serial No. 55,211

Term of patent 14 years

(Cl. D34—2)

Fig. 1 is a front perspective view of the animal figure, showing my new design; and

Fig. 2 is a rear perspective view.

I claim:

The ornamental design for an animal figure, substantially as shown.
